MARSHALL J. ROHR, OF WASHINGTON, DISTRICT OF COLUMBIA, ASSIGNOR OF ONE-FOURTH TO EMORY H. BOGLEY AND ONE-FOURTH TO JOHN W. BOGLEY, BOTH OF WASHINGTON, DISTRICT OF COLUMBIA.

ANTISKIDDING DEVICE FOR VEHICLES.

1,026,224.

Specification of Letters Patent.

Patented May 14, 1912.

Application filed December 16, 1910. Serial No. 597,884.

To all whom it may concern:

Be it known that I, MARSHALL J. ROHR, a citizen of the United States, residing at Washington, in the District of Columbia, 5 have invented new and useful Improvements in Antiskidding Devices for Vehicles, of which the following is a specification.

This invention relates to certain new and useful improvements in anti-skidding devices for vehicle wheels, and more particularly to that class in which provision is made for the ready attachment or removal of the anti-skidding device for the purpose of repairs or when it may be desired not to 15 use the same.

The present invention has for its objects among others to provide a simple and efficient yet durable device of this character, embodying removable plates having spurs 20 or projections, held by a band or bands or the like having a cavity or cavities upon its or their inner face or faces for the reception of the marginal portions of the plate or plates. This band or bands are 25 further provided with openings through which the projections of the plates pass, the material removed to form such openings being turned at substantially a right angle to the outer face of the band and embracing 30 the opposite sides of the projections or spurs of the plate and serving also as auxiliary anti-skidding devices when the projections or spurs on the plates become worn to such an extent as to present such bent-up portions 35 of the band for contact with the ground.

Other objects and advantages of the invention will hereinafter appear and the novel features thereof will be particularly 40 pointed out in the appended claim.

The invention is clearly illustrated in the accompanying drawings, which, with the numerals of reference marked thereon, form a part of this specification, and in which— 45 Figure 1 is a detail inside elevation showing the application of the invention to a pneumatic tire. Fig. 2 is an enlarged cross section showing the means for holding the band in position. Fig. 3 is a section length-

50 wise of the plate with the plate in elevation and the band in section. Fig. 4 is a side elevation of a slightly modified form. Fig. 5 is a section as on the line 5—5 of Fig. 4.

Fig. 6 is a perspective view of one of the plates removed.

55

Like numerals of reference indicate like parts throughout the different views.

Referring to the drawings, 1 designates a rim, 2 a tire, in this instance of any well known pneumatic form, and 3 the spokes of 60 a wheel to which it is desired to apply the invention. It is to be understood that as many of these anti-skidding devices as may be desired may be applied to the one wheel. As they are all substantially the same in 65 form and mode of application, a detailed description of one will suffice for all.

4 is a plate preferably of steel, curved slightly to conform to the curvature of the outer face of the tire, as will be evident 70 from Figs. 2 and 6, while upon the outer face thereof are provided any suitable number of spurs or projections 5 which may be of any desired form.

6 is a band, of steel or any other suitable 75 material, having therein openings formed by punching or otherwise forcing out the metal, the forced or punched out portions thereof being extended at substantially right angles to the outer face of the band, as seen 80 clearly in Fig. 3, forming the projections 7 which surround the openings. The inner face of the band at these points is off-set outward, so as to form a recess or cavity 8, as seen clearly in Figs. 2 and 3, for the reception of the plate 4, so that when applied, 85 as seen in Fig. 2, the inner faces of the plate and band will be substantially flush, so as to present a smooth bearing upon the outer face of the tire and prevent undue wearing 90 on the latter. In applying the anti-skidding device, the plate is first put in position from the under side of the band, the spurs or projections being forced through the openings between the flanges or projections 95 7, between each set of which the spurs 5 snugly fit, the plate being pressed firmly into the cavity 8. The ends of the band are then applied about the tire and rim and fastened in some suitable manner. I have devised a variety of ways by which this band 100 may be fastened.

In Figs. 1 and 2 I have shown the band as provided near its ends with openings or slots 9 extending transversely of the length 105 thereof and into these openings are designed

to be sprung or snapped the rolled or turned over ends 10, 10 of the supplemental member 11, as will be evident upon reference to Figs. 1 and 2. The supplemental member 11 5 is provided with a reinforce 12 into which is threaded a bolt 13 which carries upon its inner end a plate 14 adapted to bear against the rim 1, as seen clearly in Fig. 2. This bolt may be turned in any suitable manner, 10 as by a suitable handle 15 indicated in Fig. 1. 16 is a lock nut upon the bolt adapted to bear against the under face of the supplemental member 11, as seen best in Fig. 2, to lock the parts in position after the 15 parts have been tightened by screwing up the bolt. It is to be understood that after the band is placed about the tire and rim, with the plate 4 in position therein, the ends 10 of the supplemental member 11 are 20 sprung into the slots 9 of the band, the said band and supplemental member both being of spring metal or the like provided with sufficient resiliency for this purpose, and then when the bolt is screwed up, the pres- 25 sure of the plate 14 against the rim forces the band and supplemental member in opposite directions, so that the band is clamped tightly about the tire and rim. The supplemental member and the lock nut being dis- 30 posed between the spokes and beyond the rim, that is between the same and the hub, the same is in position where it is not liable to become damaged in any way.

In Figs. 4 and 5 I have shown another of 35 the numerous forms which I have devised for fastening the band 6 and its supplemental member 11 in position. In this instance, the band 6 is provided near one end with a slot 17, while the supplemental mem- 40 ber 18 provided with the reinforce 19, as before, for the passage of the bolt, has its other end hinged, as at 20, to the adjacent end of the band 6. The mode of operation is substantially the same except that the 45 rolled or turned over end 21 is sprung into the slot 17, the other end moving upon its

hinge 20, instead of both ends being sprung into slots upon the opposite ends of the band, as heretofore. In this form, the plate 14, the bolt 13 and the lock nut 16 are em- 50 ployed the same as in the form previously described.

From the above, it will be seen that I have devised a simple and efficient yet durable form of anti-skidding device applicable 55 to any and all forms of automobile tires or the like and one in which the wear plates may be readily removed or replaced when desired and yet which are so constructed and arranged as not to in any wise damage 60 the tire of the wheel; and while the structural embodiment of the invention as hereinbefore disclosed is what I at the present time consider preferable, it is evident that the same is subject to changes, variations 65 and modifications in details, proportion of parts etc. without departing from the spirit of the invention or sacrificing any of its advantages. I, therefore, do not intend to restrict myself to the precise form hereinbefore disclosed, but reserve the right to make such changes, variations and modifications as come properly within the scope of the protection prayed.

What is claimed as new is:—

In an anti-skidding device, a band offset outwardly forming a recess upon its inner face and a plurality of separated openings with surrounding projections, a plate non-rotatably held within said recess and having 75 spaced projections extending through said openings and beyond said surrounding projections and snugly embraced thereby, and means for connecting the ends of the band.

In testimony whereof I have hereunto set 80 my hand in presence of two subscribing witnesses.

MARSHALL J. ROHR.
